G. J. COOKE

EXPANSION VALVE

Original Filed April 2, 1923

Fig. 1.

UNITED STATES PATENT OFFICE.

GEORGE J. COOKE, OF CHICAGO, ILLINOIS.

EXPANSION VALVE.

Original application filed April 2, 1923, Serial No. 629,392. Divided and this application filed June 6, 1924. Serial No. 718,348.

To all whom it may concern:

Be it known that I, GEORGE J. COOKE, a citizen of the United States, residing at Chicago, in the county of Cook and State of Illinois, have invented a certain new and useful Improvement in Expansion Valves, of which the following is a specification.

This invention is a division of my prior application for refrigerating apparatus, Serial No. 629,392, filed April 2, 1923.

The invention relates to expansion valves required in machines of the class described in the above mentioned application for allowing the condensed refrigerating material usually ammonia, to expand from one part of the machine to another, thereby producing the necessary conditions for the refrigerating work of the machines.

The object of the invention is to provide a valve of this class which is much more efficient in operation than devices heretofore known, which can be easily and cheaply made, which are satisfactory in use, and is not readily liable to get out of order. More particularly the invention consists in numerous features and details of construction which will be hereafter more fully set forth in the specification and claims.

Referring to the drawings in which like numerals indicate the same parts thruout the several views,

Figure 1 is a vertical sectional detail view of the valve mechanism illustrating this invention in its preferred form.

Figure 2 is a sectional detail plan view on the irregular line 2-2 of Figure 1.

Figure 3 is a sectional end view on the irregular line 3-3 of Figure 1.

Figure 4 is a perspective end view of the valve proper.

The preferred embodiment of the device illustrated in the drawings includes a casing 8 containing at one end a socket 10 for receiving any suitable filtering material, as for example, absorbent cotton, this chamber opening thru a passage 12 into another chamber 14 from which leads a passage 16 which opens into a discharge pipe 18. The opposite end of the casing 8 contains a threaded bore 20 in which a valve proper 22 is screwed, the inner end of this valve which extends into this chamber 14 being of considerably less diameter than the internal diameter of this chamber. The inner end face of the valve 22 at the portion thereof

in line with the passage 12 contains a recess 24 which opens into a radially-extending relatively small channel 26 in this face and opening into the chamber 14. The recess 24 and channel 26 form a passageway through the end of the valve. One end of the casing 8 is equipped with a stuffing box 28 and its opposite end is provided with a union 30, the latter containing an opening 32 there-thru in which an intake pipe 34 is secured.

The mechanism just described is installed in a refrigerating apparatus, for instance that of said prior application, in such a manner that compressed material is fed in thru pipe 34 and after expanding thru passages 12, 24 and 26 it leaves the valve device thru pipe 18. In the operation of such a machine the expansion device of this invention is arranged with the valve 22 in approximately the position shown in Figures 1 and 2 of the drawing. Movement of the valve 22 by an operator applying a wrench to its non-circular end 22^a is effected to permit the valve to be partially withdrawn from the position shown in Figures 1 and 2 to the right thereof to permit the more ready cleaning of the ports of the valve structure by blowing compressed air or gas therethru.

The provision of the filtering material in the chamber 10 is of value-as it insures against the passage of particles of dirt, to the small orifice of the expansion device and which if not intercepted might clog the latter, whereby obstructing of the valve passages is reduced to the minimum.

The recess 24 and the small passage 26 at right angles to the axis of valve 22 is of importance in insuring accurate adjustment of the device.

Having thus described my invention what I claim as new and desire to secure by Letters Patent, is:-

1. An expansion device comprising a casing containing a chamber having an inlet and an outlet in communication therewith, a valve extending into said chamber, containing a passage opening thru an end of the valve into said inlet and opening thru the side of the valve into said chamber, said valve being adapted to be adjusted into a position in which its passage opens at both ends into said chamber.

2. An expansion device comprising a casing containing a chamber having an inlet and an outlet in communication therewith,

- 2
- a valve extending into said chamber, containing a passage opening thru an end of the valve into said inlet and thru the side of the valve, into said chamber, the said passage being cut into an end of the valve which normally strikes and otherwise closes said inlet passage, said valve being adapted to be adjusted into a position in which its passage opens at both ends into said chamber.
- 10 3. An expansion device comprising a casting containing a chamber having an inlet and an outlet in communication therewith, a valve extending into said chamber, contain-
- ing a passage opening thru an end of the valve into said inlet and opening thru the side of the valve into said chamber, the portion of said passage where it opens thru the side of the valve being restricted as compared with the opposite end thereof, said valve being adapted to be adjusted into a position in which its passage opens at both ends into said chamber.

In witness whereof, I have hereunto subscribed my name.

GEORGE J. COOKE.
